(57) **CLAIM**

The ornamental design for an inflatable tent on roof of a vehicle, as shown and described.

DESCRIPTION

FIG. 1 is a front and top perspective view of an inflatable tent on roof of a vehicle, showing our new design;

FIG. 2 is a rear and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of a portion labeled, 'FIG. 9' in FIG. 1;

FIG. 10 is an enlarged view of a portion labeled, 'FIG. 10' in FIG. 1;

FIG. 11 is an enlarged view of a portion labeled, 'FIG. 11' in FIG. 2; and,

FIG. 12 is a front perspective view of the inflatable tent on roof of a vehicle, showing the inflatable tent on roof of a vehicle placed on a car.

The dashed broken lines in the figures illustrate portions of the inflatable tent on roof of a vehicle that form no part of the claimed design. The dash dot dash lines in FIGS. 1, 2, 9, 10 and 11 are for the purpose of depicting the cut line of the enlarged view and form no part of the claim. The broken lines shown of a car and a ladder in FIG. 12 depict environmental structure that form no part of the claimed design.
